UNITED STATES PATENT OFFICE.

EDWARD J. DOBERSTEIN, OF BLUE ISLAND, ILLINOIS, ASSIGNOR TO GOODMAN MANUFACTURING COMPANY, OF CHICAGO, ILLINOIS, A CORPORATION OF ILLINOIS.

SCRAPER.

Application filed March 17, 1923. Serial No. 625,792.

To all whom it may concern:

Be it known that I, EDWARD J. DOBERSTEIN, a citizen of the United States, residing at Blue Island, in the county of Cook 5 and State of Illinois, have invented a new and useful Improvement in Scrapers, of which the following is a specification.

This invention relates to improvements in scrapers used for transporting loose material and more particularly to reciprocably operated scrapers having a movable closure at one end thereof operatively connected with draft ropes so as to be opened when the scraper is moved in one direction and 15 closed when the scraper is moved in the opposite direction.

The object of my invention is to provide an improved construction of a scraper of the class described.

20 My invention may best be understood by reference to the accompanying drawings which illustrate one form of embodiment of my invention, in which:

25 Figure 1 is a plan view of a scraper constructed in accordance with my invention.

Figure 2 is a sectional view taken on line 2—2 of Figure 1.

30 Figure 3 is a rear view of the scraper with parts broken away and drawn to a somewhat larger scale than Figures 1 and 2.

The apparatus comprises a scraper body 10 which may be of any desired construction and arrangement as for instance, it may comprise a pair of side walls 11, 11, 35 connected by suitable cross members 12, 13, and 14. A pair of inwardly extending flanges 15, 15 are connected to the lower margins of the side walls, the central portion of the scraper being bottomless, as 40 shown, although it may be desirable under some circumstances to provide a continuous bottom.

The scraper when in use is adapted to be moved reciprocably along the ground by 45 suitable power devices, such as a hoisting engine (not shown), having connection with the scraper through a head line 20 and a tail line 21. These lines may be arranged and guided by fixed or movable sheaves or 50 devices in any desired manner to direct the scraper reciprocably between the point of gathering and the point to which the material is to be transported and deposited.

Referring now more particularly to the

details of construction embodying my invention, I provide a movable wall at one end of the scraper adjacent the tail line 21, comprising a wall portion 25 adapted normally to extend across the rear end of the scraper to form a closure therefor, and 55 having a pair of connected side pieces, such as plates 27, 27 pivotally connected to the two side walls 11, 11, on a horizontal transverse axis, as indicated at 26, 26. In the form shown these plates are each arranged 60 inside its adjacent side wall 11, and is journaled on a bearing stud 28 mounted on said side wall. The movable end member 25 is preferably formed arcuate in cross section, as clearly shown in Figure 2, having 65 as its centre the transverse axis about which the said member is pivotally swung.

Means operably connecting the movable end member with the head rope comprises 70 a pair of flexible terminals 20^a, 20^a connected at the forward end of the scraper to the head rope 20 and each trained through suitable guides on the scraper body as for instance, a pair of vertically disposed rollers 30, 30, and horizontally disposed rollers 31, 31, and connected to the plates 27, 27. This connection may be made in any suitable manner as for instance, a looped end 20^b of each flexible terminal is passed about 75 a stud 33 mounted on a pin 34 supported between the plate 27 and a bracket 37 connected to the inner face of said plate. The pin 34 also extends through a slot 36 formed in the side wall 11, this slot being arcuate 80 in shape to permit the end member 25 to swing pivotally, the opposite ends of said slot forming stops to limit the forward and rearward movements of said end member.

85 Connection with the tail rope is provided by means of a pair of flexible terminals 21^a, 21^a connected by suitable means to studs 39, 39 on the outer ends of the pins 34, 34. It will be noted in Figure 2 that the movement 90 of the end member 25 is limited by the pins 34, 34 in slots 36, 36 so that the connections 95 between said member 25 and the draft ropes are always below the pivotal point 26 of said moving member. This arrangement provides effective leverage for operation of 100 the end member 25 in either direction of movement of the scraper.

105 It will now be clear that my improved scraper above described gathers its load at

the toe of the pile of loose material while being moved rearwardly by the tail rope, the draft on the tail rope serving to swing the end member 25 upwardly into the position shown in dotted lines in Figure 2, so that the rear margins of side walls 11, 11 of the scraper cut into the material unimpeded by said end member. When the scraper has been advanced sufficiently to gather its load, 10 the pull on the tail rope 21 is discontinued and tension is applied to the head rope 10. This tension is applied directly on the end member 25 in a direction to swing the same downwardly and is furthermore indirectly applied to the scraper so as to move the latter forwardly. The lower portion of the end member 25, being curved forwardly, will readily cut into the loose material until the end member resumes its fully closed position 20 as shown in full lines in Figure 2. The end member is preferably arcuate in section with its pivotal axis as the center thereof, as described, so as to offer a minimum resistance to the material during the closing thereof.

Among the advantages of my scraper are its simplicity of construction and positiveness in operation. The operating parts are few and simple in construction, and are 30 mounted on the side walls leaving the central part of the scraper body free and unobstructed for loading and unloading. Furthermore, the rear end member will be maintained in closed position when the draft 35 rope is pulled at various angles with respect to the longitudinal axis of the scraper, as for instance, when it is desired to turn the scraper at an angle from its normal course or forward movement.

40 Although I have shown and described one form in which my invention may be em-

bodied, it will be understood that the details of construction may vary widely for attaining objects and advantages similar to those herein disclosed without departing 45 from the spirit and scope of my invention. I do not therefore, wish to be understood as limiting myself to the specific construction illustrated herein, excepting as specifically limited in the appended claims. 50

I claim as my invention:

1. A scraper adapted for reciprocable movement along the ground and open at the forward end thereof, said scraper having side walls forming upright cutting edges at 55 the rear end thereof, a movable closure pivotally connected to be bodily swung vertically above the cutting edges at said rear end, and draft means for reciprocably moving said scraper having operable connection 60 with said closure whereby said scraper may be filled through the rear end when moved rearwardly, said closure means being movable into position to close the rear end when the scraper is moved forwardly. 65

2. A scraper adapted for reciprocable movement along the ground and open at the forward end thereof, said scraper having side walls forming upright cutting edges at 70 the rear end thereof, a rear end portion normally forming a closure therefor and curved forwardly adjacent its lower edge, said rear end portion being pivotally connected to said side walls and arranged to be bodily swung upwardly and above said cutting 75 edges, and draft means for reciprocably moving said scraper having operable connection with said rear end portion.

Signed at Chicago, in the county of Cook and State of Illinois, this 28th day of February, 1923.

EDWARD J. DOBERSTEIN.
